UNITED STATES PATENT OFFICE.

DANIEL W. COLBY, OF BOSTON, MASSACHUSETTS, ASSIGNOR TO UNITED SHOE MACHINERY COMPANY, OF PATERSON, NEW JERSEY, A CORPORATION OF NEW JERSEY.

MACHINE FOR INSERTING FASTENERS.

1,106,367.

Specification of Letters Patent. Patented Aug. 11, 1914.

Application filed December 28, 1911. Serial No. 668,289.

To all whom it may concern:

Be it known that I, DANIEL W. COLBY, a citizen of the United States, residing at Boston, in the county of Suffolk and State 5 of Massachusetts, have invented certain Improvements in Machines for Inserting Fasteners, of which the following description, in connection with the accompanying drawings, is a specification, like reference characters 10 on the drawings indicating like parts in the several figures.

The present invention relates to improvements in machines for inserting fasteners such as eyelets, lacing studs or the like.

15 The invention is herein shown as embodied in a machine of the type disclosed in Letters Patent of the United States No. 934,066 granted September 14, 1909 on an application of George Goddu, although it is 20 not limited in its application to this or any particular type of machine.

In certain eyeleting machines, of which that above mentioned is one example, the feeding movement of the work is effected be- 25 tween the insertion of successive eyelets by swinging a work engaging member about a fixed axis. Usually the work engaging member comprises a punch or setting die which is mounted in a pivoted head or lever, 30 the head or lever having imparted to it an angular movement proportional to the distance required between successive eyelets. It will be apparent that with this construc- 35 tion the path of the work feeding means is not rectilinear but curved on a radius equal to the distance of the punch or set from the pivot of the head or lever in which it is mounted. In setting eyelets having a relatively close spacing the path of the feeding 40 means departs so little from a straight line that no difficulty is experienced in properly guiding the work to setting position but, in setting large eyelets which are commonly spaced a considerable distance apart, the 45 curved movement of the feeding means becomes objectionable and allows inaccuracies to occur in the feeding operation. With these conditions in view, it is an object of the present invention to provide mechanism 50 for imparting feeding movement in a rectilinear path to a work engaging member mounted for movement with a pivoted head. As herein shown, this result is secured by arranging the pivoted head or lever, or that 55 part of the head or lever in which the work

engaging member is mounted, so that it may have imparted to it a bodily movement in a radial direction toward or from the initial position of its pivot and in providing guiding means for controlling the path of its 60 movement. One preferred form of guiding means comprises a member having a guiding surface against which runs a roller connected with the head which carries the setting die. A spring acting upon the head 65 through suitable connections serves to hold the roller in contact with said guiding surface and a cam, properly timed and operating through a cam lever and links, serves to swing the head about its pivot while its 70 feeding portion is guided in a rectilinear path by the engagement of the roller with the guiding surface.

It will be apparent that with this construction a feeding movement of a very accurate character is insured and that its accuracy is unaffected by the extent of the feeding movement or by variations in its extent. This characteristic is of much importance and a valuable feature of the in- 75 vention inasmuch as it is customary and necessary frequently to vary the extent of the feeding movement in machines of the class to which the present invention relates.

Another feature of the invention relates to 80 the hopper or magazine driving mechanism and consists broadly in providing a rigid driving shaft to actuate the agitator of a hopper mounted on a movable support such as an oscillating raceway, or raceways, 85 which it supplies. In the machine herein shown there is provided an oscillating raceway support whereby the delivery end of the raceways is moved to and from the position in which eyelets are delivered to the setting dies and the hopper which supplies said raceways is also supported on, and moved with, the oscillating raceway support. As is usual in such constructions, the hopper is 90 provided with a rotatable agitator having a spindle projecting through the bottom of the hopper. Heretofore this agitator spindle has been turned by a flexible shaft actuated from the main shaft of the machine. In accordance with the present invention it is proposed to eliminate from the machine the flexible driving shaft for the agitator and thereby improve and simplify its construction. As herein shown this is 95 effected by providing a bearing bracket 100 105 110 115

mounted adjacent to the axis of the agitator spindle so as to permit relative angular movement between itself and the oscillating raceway bracket and arranging a rigid driving shaft with one end journaled in said bearing bracket and the other journaled in suitable bearings on the machine frame. In this way the operative connection between the rigid shaft and the agitator spindle is preserved regardless of the movement of the hopper with the raceway bracket.

Still another feature of the invention relates to an improvement in the operating tools, viz., the punch or die of the machine, whereby removal of the operative part of the tool is facilitated when it is desired to sharpen or replace the tool. As herein shown the operative end of the punch, for example, is made detachable from the body portion and provided with a shoulder to receive the end of a spring catch which locks it to the body portion of the tool.

These and other features of the invention will be best understood and appreciated from the following description of a preferred embodiment thereof selected for purposes of illustration and shown in the accompanying drawings in which Figure 1 is a plan view of so much of the machine as is necessary to understand the present invention; Fig. 2 is a fragmentary view in perspective of the parts of the machine which operate upon the work showing the guideway for controlling the feeding movement; Fig. 3 is a fragmentary view in perspective showing part of the head and roller in the position which they occupy at the end of the feeding operation; Fig. 4 is a plan view showing the operating cams and levers in the positions which they occupy at the beginning of the feeding movement; Fig. 5 is a perspective view of parts of the actuating means for the agitator in disassembled relation; Fig. 6 is a sectional view of part of the head and one of the punches.

The illustrated machine, like that of said patent, comprises oppositely disposed punches 10 and oppositely disposed setting dies 12 arranged in bearings in the head 14 with the anvil or the die plate 16 also supported in said head and arranged between the oppositely disposed punches and setting dies. The anvil plate 16 carries a punching block 18 in alignment with the punches 10 and an upsetting die 20 in alignment with the setting dies 12. The head 14 is pivoted at its upper or rear end on a journal pin 22 carried by the arm 24 of a bell crank lever pivoted to the frame of the machine on a pin 26. The other arm of the bell crank lever carries a cam roller 28 which runs in a cam track 30. This cam operates to shift the head forwardly and rearwardly as will appear hereinafter.

Transverse movement of the head 14 is

effected through the links 32 and 34 and the cam lever 36 pivoted to the frame of the machine on a pin 38 and carrying a cam roller which runs in the cam track 40. The feeding movement is effected by the action of the cam lever 36 and to vary the extent of the feeding movement, and thereby the spacing of the eyelets, mechanism is provided for varying the amount of transverse movement transmitted through the links 32 and 34 to the head 14 from the cam lever 36. At the pivotal point of the links is secured another link 42 which is pivoted upon an arm 44 movable over the face of a quadrant plate 45, a stop pin 46 being provided to limit its movement and a spring 47 to hold it in position against the stop pin. The arm 44 is pivoted at its rear end to the quadrant plate 45 and it will be seen that by swinging the arm toward the right the pivotal point of the link 42 will be moved into a position in which the link 42 will guide the pivot point of the links 32 and 34 in an arc extending more or less transversely to the feeding movement of the head, a greater component of the movement of the pivot points of the links 32 and 34 becoming lost motion as the arm 44 is moved farther toward the right.

The punch and setting dies are mounted in parallel bearings in the head 14 being actuated by the cam lever 50 and retracted by the levers 52 and 54 which are lifted by the torsion springs 55. The head 14 is moved forwardly or rearwardly to bring either the punch or setting die under the end of the actuating lever 50 by the cam 30 acting through the bell crank lever 24 upon the head. Fig. 1 shows the punch arranged in operative relation to the lever 50 and those parts which are shown in Fig. 2 are in the same position.

A guide plate 56 and presser foot 57 are mounted upon a fixed part of the machine frame and serve to guide the work as it is drawn into setting position by the transverse movement of the head 14. The cam 30, which actuates the bell crank lever 24, is constructed so as to move the head 14 quickly toward the rear after the punching operation in order to bring the setting dies into alignment with the previously punched holes. The cam 30 is then widened, as shown in Fig. 4, so that it has no control on the forward and rear position of the head. The cam 30 is so shaped that at the completion of the transverse feeding movement it acts upon the roller 28 and the bell crank lever 24 to advance the head 14 forwardly, this movement taking place during a reverse transverse movement of the head and serving to restore the parts of the machine to their initial position.

To the forward side of the head 14 is secured a bracket 60 upon which is journaled

the roller 61. Rigidly mounted on the machine frame is a guide plate 62 having a transverse flange or shoulder 63 against which the roller 61 runs when the feeding movement is taking place. The flange 63 is curved or inclined very slightly in order to compensate for pivotal movement of the head so that the set shall be moved in a straight path. The curvature required in 10 the flange is indicated in Figs. 2 and 3 but is so slight as to be scarcely noticeable. It will be apparent that if the guideway were absolutely straight the path of the feeding member of the machine would depart only 15 very slightly from a straight line. Such construction would be satisfactory in many cases and is clearly within the scope of the invention. The guideway is hereinafter referred to as "substantially rectilinear" and 20 this term should be construed to cover any guideway which will bring about a rectilinear or substantially rectilinear movement of the feeding device. The head 14 is held 25 yieldingly toward the rear so that the roller 61 engages the guiding flange 63 by a tension spring 66 extending between an arm 67 on the rear end of the bell crank lever 24 and a lug on the frame of the machine. It will thus be seen that during the feeding movement of the work the path of the portion of 30 the head 14 which carries the setting dies 12 is guided in a rectilinear transverse path by the combined action of the guide flange 63, the spring 66 and the cam lever 36. The 35 initial position of the roller and head with respect to the guideway is shown in Fig. 2. In the first step in the cycle of operations the head is moved rearwardly and the roller carried into engagement with the guide 40 flange 63, this position being indicated by dotted lines in Fig. 3. During the feeding movement the roller moves to the position indicated in full lines and the setting die is guided in a substantially parallel path. In 45 the last step of the cycle the roller moves along a curved path from a position shown in Fig. 3 to that shown in Fig. 2 under the combined influence of the cams 30 and 40.

The oscillatory raceway support 70 for the 50 raceways 72 is pivoted to the machine frame at its left side, Fig. 1, and operated to swing the raceways to and from delivering position by the cam 74 acting through a cam lever 76 and a connecting link 78. The hopper 55 80 is carried by the raceways and is located above the support 70. Within the hopper is disposed an agitator 82, shown as a brush, having a finger 83 fast to its hub beneath the hopper bottom. Journaled on 60 a spindle 85 set in the support 70 is a toothed disk 86 having an upstanding pin 84 arranged to engage the finger 83 and turn the agitator when the disk 86 is rotated.

The disk 86 is rotated from the main 65 shaft of the machine by the driving shaft

90 journaled at one end in the swivel bearing bracket 88 and at the other in the bearings 94 on the machine frame. The bearing bracket 88 is swiveled or pivoted upon the spindle 85 and has a bevel gear 92 which is 70 held always in mesh with the disk 86 regardless of the position of the support 70. As the axes of the support 70 and the spindle 85 do not quite coincide it is apparent that there will be some bodily movement of the spindle 85 but since the bearing bracket is free to turn on the spindle its direction does not change and the shaft 90 is never cramped. The outer end of the shaft is arranged to slide freely in the bearing 94 75 83 on the machine frame and is turned by a belt running over a pulley 95. The sliding movement of the shaft is never sufficient in extent to interfere with the driving connection of the pulley 95 and its corresponding pulley on the main shaft. The movement of the spindle 85 from front to rear and the resulting angular movement of the shaft 90 is provided for in the bearing 94 by making its bore slightly flaring. 85 90

The construction of the punches is best illustrated in Fig. 6 wherein the head 14 is shown as having a bore for the cylindrical body portion of the punch and a channel or keyway for a latch piece 99 secured to the body of the punch and arranged to hook over a shoulder formed on the detachable end portion, thus serving to hold the two portions together. When it is desired to replace the end portion of the punch, the 100 punch is forced out of the head sufficiently to permit the latch piece to be lifted, whereupon the end portion may be slipped out of its holder. 95

Having now described my invention, what 105 I claim as new and desire to secure by Letters Patent of the United States is:—

1. A machine of the class described having, in combination, work guiding means, fastener inserting means including a work 110 feeding member arranged to engage the work intermittently and being mounted for pivotal movement while in engagement therewith, a substantially rectilinear guideway for controlling part of the movement 115 of said feeding member, and means for actuating said member.

2. A machine of the class described having, in combination, a movable head, a work feeding member mounted therein, a substantially rectilinear guideway arranged to control the feeding movement of said head, and means for returning said head to its initial position along a path independent of said guideway. 120

3. A machine of the class described having, in combination, a movable head, a work feeding member mounted therein, a guideway, a roller mounted on said head and arranged to run upon said guideway to control 125 130

- the feeding movement of said head, and means for returning said head to its initial position along a path in which the roller is out of engagement with said guideway.
5. A machine of the class described having, in combination, a work feeding member movable toward and from the work to engage and disengage the same and movable also in a substantially triangular path in 10 part of which it feeds the work, and a stationary guideway for controlling its movement along one side of said path.
5. A machine of the class described having, in combination, a work feeding member 15 movable in a three-sided path, cams and connections for controlling said member while moving along two sides of said path, and a guideway for controlling its movement along the third side of said path.
20. 6. A machine of the class described having, in combination, a work feeding member movable in a three-sided path, a cam arranged to move said member along one side of the path, a guideway for controlling its 25 movement along the second side of said path, and a second cam for effecting said latter movement, both of said cams coöperating to return said member to its initial position along the third side of said path.
30. 7. A machine of the class described having, in combination, a pivotally mounted head, means to swing the head about its pivot, means to guide the outer end of the 35 head in a path tangential to an arc described about the pivot of the head, said path being substantially rectilinear throughout its extent, and means for moving said head radially, said means being ineffective during the movement of the head in said tangential 40 path.
45. 8. A machine of the class described having, in combination, a pivotally mounted head, a cam for swinging the head about its pivot, means to guide the outer part of said head in a path tangential to an arc described about the pivot of the head, and a cam for moving said head radially, said cam being ineffective during the movement of the head in said tangential path.
50. 9. A machine of the class described having, in combination, a pivotally mounted head, means for swinging the head about its pivot, a fixed guideway for the outer part of 55 said head, and a cam for moving said head radially, said cam having a wide portion arranged so as to leave the head free from its control during the movement of the head along said guideway.
60. 10. A machine of the class described having, in combination, a pivotally mounted head, a work feeding member mounted therein, means for moving said head so that the

feeding member shall traverse a three-sided path, means for guiding said member in a rectilinear path in its movement along one 65 side of said path, and means for varying the extent of movement of the member along that side of the path without affecting the direction of movement.

11. A machine of the class described having, in combination, a pivotally mounted head, a work feeding member therein, a bracket attached to the head at a point remote from its pivot, a guide roller journaled in the bracket, and a stationary guiding 75 member coöperating with the roller to control the movement of the head.

12. A machine of the class described having, in combination, a movable support for a hopper, an agitator turning member movable with the support, a bearing bracket arranged to swivel about the axis of the agitator turning member, and a driving shaft 80 for said member journaled in the bracket.

13. A machine of the class described having, in combination, a movable support, a spindle movable therewith, a bracket swiveled about the spindle, a driving shaft having a stationary bearing at one end and being journaled at its other end in said bracket, 90 and an agitator actuating device mounted upon the spindle and driven by the shaft.

14. A machine for setting fasteners having, in combination, a setting die, a die-carrying member mounted to swing about an axis at the rear of the die, and being also movable radially with respect to its axis, a cam and connections for swinging the die-carrying member, and a transverse guiding cam for so controlling the radial movement 100 of the die-carrying member that the movement of the die shall take place in a substantially rectilinear path.

15. A machine for setting fasteners having, in combination, a work feeding tool, a carrying member for the tool mounted to swing about an axis at the rear of the tool and being also movable radially with respect to its axis, and a guiding cam extending transversely with respect to the carrying member and acting to cause such radial movement of the carrying member when the latter is swung about its axis that the work feeding path of the tool is in a path tangential to an arc described about the axis of the head.

In testimony whereof I have signed my name to this specification in the presence of two subscribing witnesses.
